CLAIM

I claim the ornamental design for a table, as shown and described.

DESCRIPTION

FIG. 1 is a top plan view of a table, showing, my new design; FIG. 2 is a front elevation view thereof the back and side elevation views being a mirror image thereof;

FIG. 3 is a bottom plan view thereof;

FIG. 4 is a top perspective view thereof; and,

FIG. 5 is a bottom perspective view thereof.

The broken line portion of the drawings is included to show portions of the article that forms no part of the claimed design.
